PRINTING PLATE CLAMP

Carl C. Sweet, Milwaukee, Wis., assignor to C. B.
Cottrell & Sons Company, Westerly, R. I., a corporation of Delaware

Application April 22, 1939, Serial No. 269,341

3 Claims. (Cl. 101—388)

My invention relates to improvement in printing plate clamps which are commonly known as printers' register hooks, in which the register hooks are propelled along a grooved base to bring 5 the jaws into and out of their plate clamping positions.

The object of my invention is to provide a double lock hook in which one lock is formed integral with and turned by the hook jaw and the other lock is turned by a key such as the key 10 which is used to propel the hook along the groove in the base by the coaction of a gear carried by the hook and a rack carried by the base.

A further object of my invention is to provide 15 a printer's register hook in which the rack engaging gear is located between the two locks so as to rigidly hold the hook against lost motion with respect to the plate and its base.

A still further object is to provide spring 20 means for yieldingly holding the two locks and thereby the hook in their adjusted positions.

A practical embodiment of my invention is represented in the accompanying drawings, in which 25 Fig. 1 represents a detail plan view showing a printing plate clamped to its base;

Fig. 2 represents a detail longitudinal section taken in the plane of the line II—II of Fig. 1;

Fig. 3 represents a detail cross section taken in 30 the plane of the line III—III of Fig. 2;

Fig. 4 represents a detail longitudinal section taken in the plane of the line IV—IV of Fig. 3;

Fig. 5 represents a detail cross section taken in 35 the plane of the line V—V of Fig. 4;

Fig. 6 represents a detail cross section taken in the plane of the line VI—VI of Fig. 4;

Fig. 7 represents a detail plan view of the hook 40 and its adjacent parts;

Fig. 8 represents a detail horizontal section taken in the plane of the line VIII—VIII of Fig. 4; 45 the two locks being shown in their locked position with respect to the base;

Fig. 9 represents a similar detail section with the locks shown in their released position, housed 50 within the hook body;

Fig. 10 represents a detail horizontal section taken in the plane of the line X—X of Fig. 2;

Fig. 11 represents an inside face view of one 55 of the half members of the hook body with the operating parts removed;

Fig. 12 represents a similar view of the other half member of the hook body with the operating parts removed;

Fig. 13 represents a side view of a key suitable 55 for use in propelling the hook along its groove

and for turning one of the locks into and out of its operative position; and

Fig. 14 represents an edge view of the said key.

The means which I have shown for securing the printing plate in register comprises generally a suitable grooved base and a register hook 5 manually propelled along the base into and out of its plate clamping position. The grooved base may have a flat or curved surface. In the present instance the base is shown as a plate cylinder 1, its cylindrical surface being provided with a plurality of longitudinally disposed helical grooves 2 having racks 3 along their bottom walls and overhanging ledges 4 along the outer portions of their side walls as is usual. The body 10 15 of the hook is divided vertically and longitudinally into two half members which are removably fastened together as by screws 6. This hook body is elongated lengthwise and it is shaped to permit its insertion into and its removal from its groove 2 when the hook is unlocked from the base. The jaw 7 and the double winged lock 8 are formed integral to produce a combined jaw and lock whereby the lock 8 may be turned into and out of its locking position by the manipulation of the jaw 7. A neck 9 connects the jaw 7 with the lock 8, which neck is journaled in a suitable vertical opening 10 in the hook body, which opening 10 extends upwardly through the 20 top of the body and also downwardly into a recess 11 opening through the sides of the body 25 and shaped to receive the double winged lock 8. 30

A second double winged lock 12 has a hollow central boss 13 which is journaled in an opening 14, which opening extends upwardly through the top of the body and also downwardly into a recess 15 opening through the sides of the body 35 and shaped to receive the said double winged lock 12. This lock 12 is turned into and out of its locking engagement with the base by means of a suitable instrument such as the key 16 having a shank 17, non-circular in cross section, adapted to fit a vertical recess 18 of non-circular cross section in the lock, which recess 18 opens through the top of the hook body. 40 45

The means which coacts with the rack 3 in the groove 2 of the base 1 for propelling the register hook into and out of its clamping engagement with the plate is shown as comprising the following elements. The rack-engaging horizontally disposed gear 19 is located in a recess 20 in the hook body and its shaft 21 is journaled in openings 22 in the sides of the body. A gear-engaging vertically disposed worm 23 is located in a 50 55

recess 24 in the body, and its upper and lower shaft extensions 25 and 26 are respectively journaled in the openings 27 and 28 in the top and bottom of the body. The opening 27 communicates with the recess 11 in which the lock 8 is located.

This hook propelling means is operated by the key 16 whose shank 17 may be inserted through the bore 29 of the combined jaw and lock into the vertical recess 30, of non-circular cross section, in the worm 23.

Spring means are employed for yieldingly holding both the lock 8 and lock 12 in their adjusted positions. In the present instance the lock 8 is yieldingly held in its adjusted position by a spring pressed ball 31 located in a recess 32 in the hook body; and the lock 12 is yieldingly held in its adjusted position by a spring pressed ball 33 located in the recess 34 in the hook body.

20 It will be observed that while the lock 8 may be turned by the manipulation of the jaw 7, the lock 12 must be turned by a key. It will also be observed that the rack-engaging gear 19 is located between the locks 8 and 12 so that a rigid position 25 of the hook within the groove upon both sides of the said gear may be obtained when the hook is locked therein.

It will also be understood that the locks and jaw as well as the hooks may be of any well 30 known or approved shape, such for instance as substantially that shown and more specifically described in United States Letters Patent 1,486,323, dated March 11, 1924.

It is evident that various changes may be 35 sorted to in the construction, form and arrangement of the several parts without departing from the spirit and scope of my invention, and hence I do not intend to be limited to the particular embodiment herein shown and described, but

40 What I claim is:

1. In a double lock printer's register hook, a body comprising vertically disposed side members having recesses therein, a turnable plate clamping jaw, a lock formed integral therewith and 45 operated thereby, a second turnable lock spaced from the first lock and operated by a removable key, lock retaining means, said side members be-

ing provided with cooperating recesses adapted to receive said locks together with the lock retaining means, and a hook propelling means including a horizontal shaft, a single gear only mounted thereon and located between and entirely below said lock containing recesses and projecting through cooperating bottom recesses in said side members. 5

2. In a double lock printer's register hook, a body comprising vertically disposed side members 10 having recesses therein, a turnable plate clamping jaw, a lock formed integral therewith and operated thereby, a second turnable lock spaced from the first lock and operated by a removable key, lock retaining means, said side members being 15 provided with cooperating recesses adapted to receive said locks together with the lock retaining means, said locks being swingably mounted in and adapted for projection through recesses in the upper portions of the side members, and a key 20 operated hook propelling means including a horizontal shaft, a single rack engaging gear only mounted thereon and located between and entirely below said lock containing recesses and projecting through cooperating bottom recesses 25 in said side members.

3. A plate holding means including a base, a groove therein, a rack extending along the bottom of the groove and a double lock register hook comprising a body slidable along 30 said groove, said body including vertical side members having recesses therein, a turnable plate clamping jaw, a lock formed integral therewith and operated thereby, a second lock spaced from the first lock and operated by a removable key, 35 lock retaining means, said side members being provided with cooperating recesses adapted to receive said locks together with the lock retaining means, and a hook propelling means including a horizontal shaft, a single rack engaging 40 gear only mounted thereon and located between and entirely below said lock containing recesses and projecting through cooperating bottom recesses in the side members for coaction with said rack. 45
